BUILDING CONSTRUCTION

Walter H. Venzie, Philadelphia, Pa.

Application March 2, 1938, Serial No. 193,549

7 Claims.

(Cl. 72—118)

The invention relates to building construction, and, more particularly, to the interior walls and ceiling in which plaster board or similar panels are used.

Common defects, either alone or concurrently, of prior wall and ceiling construction include a failure to rigidly space the plaster boards away from the furring so as to reduce the transmission of sound through the walls, a failure to support the faces of the boards so that they will not sag away from their supports when a coat of wet plaster is applied and a failure to provide clips for supporting plaster boards that will both properly position them and provide means for connecting a face supporting means to the furring.

The present invention is applicable to a wall or ceiling construction and comprises conventional furring on which suitable panels such as plaster board may be supported. The panels preferably may be connected to the furring strips by novel clips which not only space the boards from the furring strips but also provide means for engaging tie wires passing from clip to clip across the faces of the boards to support the faces. Thus the clips also serve as means for connecting the tie wires to the furring strips.

A primary object of the invention is to provide a novel wall and ceiling structure in which the surfacing units are spaced rigidly a fixed distance from their supporting furring strips.

Another primary object of the invention is to provide a novel wall and ceiling structure in which the faces of surfacing units are supported by wires which extend across their faces solely but which are connected to furring strips by clips which also support the panels.

A further object of the invention is to provide, in a wall structure using panels as the base to which a coat, or coats, of plaster is applied, clips serving as means not only for connecting panels to furring strips but also for spacing them a predetermined distance away from the strips and additionally for connecting wire passing across the faces of the boards to the furring strips.

A more specific object of the invention is to provide a novel clip including means for supporting plaster boards, means for spacing the boards from the support for the clip, means for preventing rotative movement of the clip and means providing a seat for wires.

Other objects and advantages of the invention will be apparent from the following specification, claims and from the drawing, illustrating the preferred embodiment of the invention, in which:

Fig. 1 is a vertical elevation of a wall embodying the invention;

Fig. 2 is a vertical sectional view taken through the wall shown in Fig. 1;

Figs. 3, 4 and 5 are, respectively, front and rear

elevations and plan view of the clip embodied in the invention; and

Fig. 6 is an end view of the clip positioned as in Fig. 2.

5 A wall embodying my invention may comprise furring strips herein illustrated as plasterer's channels 10 erected in any preferred or conventional manner to which panels 11 such as those commonly nominated "plaster board" may be connected by clips 12.

The clips 12 preferably are stamped from a single metal blank, each having a plate 13 one face of which rests upon the upper edge of a plaster board and the other face of which supports the

15 lower edge of another plaster board. From opposite sides adjacent one end of the plate 13 extend upwardly a pair of opposed fingers 14 and 15, the fingers lying in parallel planes normal to the plane of the plate. Similar fingers 16 and 17

20 extend from opposite sides adjacent the opposite end of the plate, the finger 16 lying in the plane of the finger 14 and the finger 17 lying in the plane of the finger 15. The four fingers 14, 15, 16 and 17 provide means for positioning panel

25 11 fixedly with respect to the upper face of the plate 13. Intermediate the fingers 14 and 16 and in the same plane therewith but extending in an opposite direction from the plane 13 is a finger 18, facing which is a finger 19 lying in the same

30 plane as the fingers 15 and 17, the two providing means for engaging the upper edge of another panel and positioning it with respect to the lower face of the plate 13. The end of each of the fingers 14 to 19, inclusive, preferably is turned outwardly with respect to the plate 13 as at 20 so that panel may be readily slipped between the fingers without tearing the usual paper covering thereon.

40 A leg 21 extends from the plate 13 in the same plane therewith inwardly (with respect to the wall) and may have a ridge embossed thereon as at 22 to increase its rigidity. Preferably the end of the leg 21 is turned downwardly and carries a finger 23, the bent down end and the finger 23

45 lying in a plane normal to the plane of the plate 13.

50 A short leg 24 extends from the plate 13 adjacent the leg 21 and carries at its end a downwardly extending finger 25 also lying in a plane normal to the plane of the plate 13 and facing the finger 23. In actual building practice the plasterer's channels are of a uniform size and the clip, in manufacture, is so sized that the conventional channel will fit snugly between the fingers 23 and 25 as shown in Figs. 2 and 5. After

55 the clip is positioned on the channel the end of the finger 23 may be bent around the channel as shown in dotted lines in Fig. 5 to hold the clip in position. It will be obvious from a consider-

ation of Figs. 2 and 5 that the relative positions of the fingers 23 and 25 precludes rotary movement of the clip in a vertical plane about the channel and such movement is the one that would otherwise be imparted to it when the plaster boards are positioned in a wall. It is further to be noted that the finger 25 and the short leg 24 space the plate 13, the panel positioning fingers 14 and 16 and hence the panels 11 away from the channel 10 so that sound waves impinging against the panels are not conducted into or through the wall. This is accomplished without any loss in rigidity of the structure so that sound transmission is minimized without causing a resiliency in the wall that previously sometimes resulted in the formation of cracks in the plaster.

Frequently in the past, where the admittedly most rapid way of erecting a wall using clips and plaster boards was followed, the application of a coat of plaster to the plaster board caused the boards to warp or sag thus destroying at a number of points the bond between the boards and the coat of plaster. To overcome this bad result the additional cost of temporarily supporting the rough coat of plaster was necessitated. The present invention overcomes this difficulty by the provision of tie wires 30 extending across the face of the board. The wires 30 are held by oppositely facing hooks 31 and 32 stamped in the finger 19 of each of the clips 12. As illustrated it is preferred that the wire extend around the lower hook 32 of one clip and the upper hook 31 of a lower clip with the ends of the wire twisted together into a knot to form a closed bight extending across the face and one edge of a board between two spaced clips.

In erecting the above described wall it will be obvious that the positioning of the furring strips will necessarily align the clips and also the wires, that the clips will be tied together vertically, that the wires will be tied together vertically and that the wires will be tied by the clips to the furring strips. An obvious modification which suggests itself is illustrated in Fig. 3 where is shown oppositely extending hooks 36 and 37 on each of the outer upwardly extending fingers 15 and 17. Thus the wires may be connected in any of the ways indicated on the right side of Fig. 1.

Various modifications may be made in the above described embodiment of my invention without departing from the spirit and scope thereof as defined in the following claims, it being understood that the words "wall" and "ceiling" wherever used are interchangeable and that the use of one or the other in the claims is not to be construed as a limitation to the use of the invention in a particular plane.

I claim as my invention:

1. In interior wall construction the combination with a support and a multiplicity of panels, of means for connecting said panels to said support and supporting their faces, comprising clips connected to said support, means forming a part of said clips for engaging said panels, and wires engaging only said clips, said wires lying wholly on the room side of said panels, extending over at least one edge of said panels, and each forming a closed bight connecting two of said clips.

2. In interior wall construction the combination with a support and a multiplicity of panels,

of means for connecting said panels to said support and supporting their faces, comprising clips connected to said support, means forming a part of said clips for engaging said panels, and wires connecting adjacent clips one to the other, each connecting wire extending across the face of one of said panels.

3. In interior wall construction the combination with a support and a multiplicity of panels, of means for connecting said panels to said support and supporting their faces, comprising clips connected to said support, means forming a part of said clips for engaging said panels, and wires connecting adjacent clips one to the other, said wires lying wholly on the room side of said panels and extending over at least one edge of a panel.

4. In interior wall construction the combination with a support and a multiplicity of panels, of means for connecting said panels to said support and supporting their faces, comprising clips connected to said support, means forming a part of said clips for engaging said panels, means extending from said clip for rigidly spacing said panels from said support, and a wire engaging only said clips, said wires each forming a closed bight across the face of a panel connecting two of said clips.

5. A clip comprising a plate having faces forming bearing surfaces for the edges of plaster board panels, two pairs of parallel fingers having opposed flat surfaces extending from the sides of said plate adjacent its ends in planes normal to the plane of said plate; another pair of fingers extending from said plate in the same planes as the first mentioned fingers but in an opposite direction, and intermediate said first two pairs, all of said fingers providing means for positioning said panels with respect to said plate, a single finger extending from said plate in a plane parallel to the planes of the other fingers but spaced therefrom, an arm on said plate positioned adjacent said last named finger lying in the plane of said plate, a finger extending from said arm in a plane parallel to the planes of the other fingers, and wire engaging means on at least one of said fingers.

6. A clip comprising a plate having faces forming bearing surfaces for the edges of plaster board panels, two pairs of fingers providing means for positioning said panels with respect to said faces, a single finger extending from said plate in a plane parallel to the plane of the other fingers but spaced therefrom, means for connecting said plate to a support, and wire engaging means on at least one of said fingers.

7. A clip comprising a plate forming a bearing surface for the edges of plaster board panels, two pairs of parallel fingers having opposed flat surfaces extending from the sides of said plate adjacent its ends in planes normal to the plane of said plate, another pair of fingers extending from said plate in the same planes as the first mentioned fingers but in an opposite direction, and intermediate said first two pairs, a single finger extending from said plate in a plane parallel to the plane of the other fingers but spaced therefrom, means for connecting said plate to a support, and hooks comprising wire engaging means on at least one of said fingers.
